UNITED STATES PATENT OFFICE.

CHARLES O. EKSTADT, OF ORION, ILLINOIS.

CONVEYER.

Application filed August 30, 1922. Serial No. 585,232.

To all whom it may concern:

Be it known that I, CHARLES O. EKSTADT, a citizen of the United States, and a resident of Orion, in the county of Henry and State 5 of Illinois, have invented a new and Improved Conveyer, of which the following is a description.

My invention relates to a conveyer and more particularly to a gravity conveyer for 10 the conveying of material or goods in bags, crates, cases, kegs, barrels or drums or for cement blocks, stone, etc.

The general object of my invention is to provide a conveyer characterized by simplicity, low cost, and portability and by the use of which great economy of time and labor results as for example in the conveying of materials or articles from a freight car to a house or to a point more or less distant with the minimum handling.

Reference is to be had to the accompanying drawings forming a part of this specification, it being understood that the drawings are merely illustrative of one example of 25 the invention.

Figure 1 is a side elevation of a conveyer embodying my invention;

Figure 2 is a plan view thereof;

Figure 3 is an enlarged side elevation of 30 a fragment of the conveyer;

Figure 4 is a cross section on the line 4—4, Figure 3;

Figure 5 is an elevation of the supporting structure and track at a joint where the 35 conveyer is to be given considerable length.

In carrying out my invention in accordance with the illustrated example, an elongated supporting structure 10 is provided here shown as having legs 11, said structure 40 consisting either of a plurality of beams placed end to end or of a single beam. On a side of the supporting structure 10 are brackets 12 flaring rearwardly from a central vertically disposed front 13 of each 45 bracket, said vertical front having secured thereto by brazing, welding or any other suitable means, a track 14 consisting of flat metal disposed vertically and projecting at its upper and lower edges above and below 50 the fronts 13 of the brackets 12. Said brackets 12 terminate in a vertical plane and are secured by any suitable fasteners 12^a to the vertical side faces of the support 10.

Where a plurality of supporting beams 55 10 are to be joined a cap plate 15 may be provided at the joint and overlapping the

adjacent ends of the beams, said plate being secured by screws 16 or the like to the respective beams. At a joint also a bottom bearing bar 17 extends across the joint and 60 secured as by bolts 18 to the structure 10 at the adjacent ends of the beams. The butt ends of adjacent rail sections 14 at the joint are inter-engaged by a mortise and tenon as at 19.

The track rails 14 are disposed in pairs at the sides of each elongated support 10 and below the same and travelling on the respective tracks are carriages 20 made suitable in practice for carrying of any particular 70 material, the carriages being shown as having plain flat tops in the present example to receive a bag A containing cement for example. The structure 10 is inclined, the legs 11 at one end being higher than the 75 other so that the material is conveyed by gravity from the upper end to the lower end. Secured to the carriage on the respective tracks is a rope or cable 30 running over pulleys 31 at the upper end of the structure. The arrangement is such that a load, 80 as for instance a bag A, placed on the upper end of the conveyer will travel downwardly by its own gravity to the lower end thereby returning the empty carriage on the other track to the upper end so that the carriages are used alternately conveying the material 85 from a freight car B to a cement house, for example, conventionally indicated at C.

The wheels 21 of the carriages are within 90 U-shaped housings 22 arching over the wheels at the top, the outer leg or side of each housing being the longer and continued below the rails 14, the lower edge 23 being turned laterally inward and upward 95 beneath the adjacent track rail 14. The pin or axle 24 of each wheel 21 passes through the opposite sides of the U-shaped housing 22 and is riveted thereto in practice. On the shorter inner sides of the housing 22 at their 100 edges are carried, by means of hinge pins 25, hangers 26 depending from the brackets 27 which carry the carriages 20. The numeral 28 indicates the hinge knuckles on the housings 22 and the numeral 29 the 105 hinge knuckles on the hangers 26. The described arrangement makes for flexibility in the carriage and at the same time prevents derailing thereof.

I would state in conclusion that while the 110 illustrated example constitutes a practical embodiment of my invention, I do not limit

myself strictly to the exact details herein illustrated, since, manifestly, the same can be considerably varied without departure from the spirit of the invention as defined in the appended claims.

Having thus described my invention, I claim:

1. A conveyer comprising a pair of supporting beams, brackets secured to the opposite vertical side faces of said beams, said brackets having approximately central portions disposed laterally outward of the beam, track rails on said central portions of the brackets, the upper and lower edges of the rails extending respectively above and below the brackets, a carriage having wheels travelling on the track rails of each beam, housings in which said wheels are journaled, and elements secured to the carriages and having depending hangers secured to said housings at the inner sides of the wheels.
2. A conveyer comprising a supporting structure having pairs of rails, a pair of carriages having wheels to run on said rails,

and housings secured to the carriages and forming bearings for the axles of the wheels, said housings at the outer sides extending below the wheels and tracks and having their lower edges directed inwardly and upwardly beneath the rails.

30

3. A conveyer including a supporting structure, pairs of track rails thereon, a carriage for each pair of rails, carriage wheels in pairs, housings arching over said wheels, and brackets on the under side of the carriages hingedly secured to said housings.

4. A conveyer including a supporting structure, pairs of track rails thereon, a carriage for each pair of rails, carriage wheels in pairs, housings arching over said wheels, and brackets on the under side of the carriages hingedly secured to said housings, the lower edges of said housings at the outer sides of the latter turned inwardly and upwardly beneath the rails.
